United States Patent Office

Des. 189,530
Patented Jan. 3, 1961

189,530

AUTOMOBILE

Friedrich K. H. Nallinger, Stuttgart, and Karl Wilfert,
Stuttgart-Degerloch, Germany, assignors to Daimler-
Benz Aktiengesellschaft, Stuttgart-Unterturkheim, Ger-
many

Filed Jan. 4, 1960, Ser. No. 58,902

Claims priority, application Germany July 4, 1959

Term of patent 7 years

(Cl. D14—3)

FIG.4

Figure 1 is a side elevational view of an automobile showing our new design;

Figure 2 is a plan view thereof;

Figure 3 is a front elevation of the automobile; and

Figure 4 is a rear elevation.

The dominant features of our design reside in the portions shown in solid lines on the drawings.

We claim:

The ornamental design for an automobile, substantially as shown and described.
